UNITED STATES PATENT OFFICE.

MATHIS J. SLUUS, OF ELMWOOD, CONNECTICUT.

SAFETY APPLIANCE FOR GAS-VALVES.

1,127,300.

Specification of Letters Patent.

Patented Feb. 2, 1915.

Application filed April 24, 1912. Serial No. 692,948.

To all whom it may concern:

Be it known that I, MATHIS J. SLUUS, a citizen of the United States, residing at Elmwood, in the county of Hartford and State of Connecticut, have invented new and useful Improvements in Safety Appliances for Gas-Valves, of which the following is a specification.

This invention relates to a safety device for gas valves, and the objects of the same are, to provide an appliance of the above nature which can be readily attached or detached to or from an ordinary gas jet, one which affords facilities for obtaining proper adjustment of the locking member, to provide means for holding the locking member securely in place and one which consists of but a few simple parts whereby it may be easily manufactured and placed upon the market at a very small cost.

With the above and other objects in view, my invention relates to such details of construction and in the arrangement and combination of the several parts as will be hereinafter described and specifically pointed out in the appended claims.

When describing my invention in detail, reference will be had to the accompanying drawings wherein like characters denote like or corresponding parts throughout the several views, and in which,

Figure 1 is a side elevation of my invention, however parts of the same have been shown in section. Fig. 2 is a perspective view of my invention. Fig. 3 is an end view of the same.

In the accompanying drawings wherein is illustrated the preferred form of my invention, the numeral 1 designates an ordinary gas jet, which gas jet is provided with the ordinary supporting structure 2 for the tip 3. The above mentioned structure is well known in this art, and I desire it to be understood that I do not make any claim in regard to this.

The jet is controlled by a valve 4, which is of the ordinary turning plug type, and which is adjusted through the medium of a set screw 5 and operated by a handle 6, as is obvious. For the purpose of limiting the rotation of the valve a nut 7 is provided upon the jet, which nut has a shoulder 8 formed thereon, against which abuts a pin 9 which is carried by the stem of the valve. My invention comprises the plates 10 and 10' which are mounted upon a rod 11, one

being held fast thereto, while the other is slidably mounted thereon through the medium of the means hereinafter set forth. A collar is provided, which consists of the sections 12 and 13, which sections are secured together by the pins 14, and have depending therefrom, fingers 15, as shown. The stationary plate 10 has engagement with the fingers above mentioned and is held in place through the medium of the members 16, said members 16 being of any adaptable form. The collar is adapted to be secured to the jet, as shown in Fig. 1, thereby holding the rod 11, parallel with the same and permitting the slidable plate 10 to be moved into or out of engagement with the handle 6 of the valve.

For the purpose of holding the slidable plate 10' rigid at different positions upon the rod 11, the said rod is provided with longitudinally extending grooves 17 into which projects a pawl 18, which pawl is carried by slide 19, the said slide being mounted within the guide way 20 upon the slidable plate 10. The slide is held in its lowermost position and the pawl in engagement with the groove through the medium of an elastic member 21, which member is of any suitable form, a coil spring having been shown in the drawings.

It is readily obvious that the slide may be moved so as to abut the handle of the valve in such a manner as to prevent the accidental rotation of the same, and hence the escape of the gas from the jet.

I desire to lay the greatest of stress upon the simplicity of my invention, and it is thought that the advantages and novel features of the same will be readily appreciated from the foregoing disclosure.

I desire it to be understood that I may make slight changes in the construction and in the arrangements and combination of the several parts, provided such changes fall within the scope of the subjoined claims.

Having thus fully described my invention, what I desire to secure by Letters Patent is:

1. In combination, a conduit pipe, a valve in said pipe having its stem provided with an operating head, a collar adjustably mounted upon said conduit pipe, supporting strips carried by said collar, a plate carried by said strips, a rod extending from said plate substantially parallel to said pipe and provided with a longitudinally extending slot,

an adjustable plate slidably mounted upon said rod, guides carried by said adjustable plate, a plunger slidably mounted in said guides and provided with a tooth for fitting 5 into said slot to prevent said adjustable plate from rotating upon said rod, and a spring carried by said adjustable plate and engaging said plunger to normally hold said tooth in said slot whereby said plate may 10 be held in an adjusted position upon said rod for engaging the operating head of the valve stem and to prevent rotation of the adjustable plate.

2. A device of the character described 15 comprising an attaching collar, arms ex-

tending from said collar, a plate carried by said arms, a rod extending from said plate and provided with a longitudinally extending groove, an adjustable plate slidably mounted upon said rod, a plunger slidably connected with said adjustable plate and provided with a tooth for fitting into said groove, and a spring carried by said adjustable plate for normally holding said tooth in said groove whereby said adjustable plate 25 may be held in an adjusted position.

MATHIS J. SLUUS.
